UNITED STATES PATENT OFFICE.

HUBBARD F. HURD, OF TROY, NEW YORK, ASSIGNOR TO CLUETT, PEABODY & CO., INC.,
OF TROY, NEW YORK, A CORPORATION OF NEW YORK.

FOLD-COLLAR.

1,213,493.

Specification of Letters Patent. Patented Jan. 23, 1917.

Application filed July 25, 1914. Serial No. 853,147.

To all whom it may concern:

Be it known that I, HUBBARD F. HURD, a citizen of the United States, residing at Troy, county of Rensselaer, and State of New York, have invented certain new and useful Improvements in Fold-Collars, of which the following is a specification.

The invention relates to such improvements, and consists of the novel construction hereinafter described and subsequently claimed.

Reference may be had to the accompanying drawings, and the reference characters marked thereon which form a part of this specification. Similar characters refer to similar parts in the several figures therein.

Figure 1 of the drawings is a front view of a fold-collar with its ends buttoned together in the position assumed in use. Fig. 2 is a plan view of a broken-away portion of the collar showing the hook-end of the band, and the neighboring portion of the top opened out flat.

In the drawings the dimensions are somewhat exaggerated for convenience of illustration.

The invention relates to fold-collars of the prevailing type having a high band and a top-portion folded over upon the band.

The principal objects of the invention are to more effectively hold in position the ends of the collar, and to improve the appearance of the collar in use. Collars of this type are commonly made with one end of the band extended to form a more or less upturned hook adapted to be embraced between the band and top at the other end of the collar in use, said hook tending to prevent displacement of the ends of the collar.

It is desirable to have the upper corners of the folded-over top lie snugly together in use, and various devices have been suggested for the purpose of rendering the hook-end of the band more effective to accomplish this result. In the manufacture of such collars it has heretofore been customary to extend the upper edge of the hook-end of the band for a considerable distance beyond its point of junction with the top of the collar, along the general line or direction of the upper edge of the neighboring attached portion of the band, or to form a concave upper edge on the hook-end of the band

extending from said point of junction to substantially the upper outer corner of said hook-end. In either of said described constructions the result is to cause the hook-end of the band to effectively engage the top of the groove formed between the band and folded-over top at the other end of the collar, only at a point remote from the neighboring corner of the folded-over top.

I have ascertained that by forming the hook-end of the band with its upper edge convexly curved immediately adjacent to its point of junction with the top, the upper edge of the hook-end of the band can be made to make effective contact throughout substantially its entire length with the top of the groove formed between the band and folded-over top at the other end of the collar, thus offering increased resistance both by leverage and by frictional contact, to the pulling apart of the ends of the collar when fastened together by the usual stud or button.

Referring to the drawings wherein the invention is shown in preferred form, 1 is the folded-over top, and 2 is the band of the collar having the upturned hook-end, 3, of the upper edge, 4, of which is convexly curved from the point, 5, of its junction with the top to substantially the upper outer corner of the hook-end. The top-edge of the attached-portion of the band is also convexly curved as shown at 6, adjacent to the point of junction of each end of the top with the upper edge of the band, whereby the front of the collar is caused to dip below the level of the back-portion of the collar, as shown at 7 in Fig. 1. The curved portions, 4 and 6, of the upper edge of the band at the hook-end of the collar are thus caused to diverge convexly from their point of intersection, 5, at the junction of the neighboring end of the top with the band.

When the ends of the collar are buttoned together in the position shown in Fig. 1, the curved edge, 4, on the hook-end of the band will fit snugly against the top of the groove formed between the band and top along the curved upper edge, 6, of the band at the other end of the collar to accomplish the desired result, so that when the collar is in use, its ends are effectively hooked together.

I prefer to have the curved edges, 4 and

6. intersect at the point of junction, 5, of the neighboring end of the top with the band, or as near such point of junction as is practicable with due allowance for inaccuracy of manufacture.

What I claim as new and desire to secure by Letters Patent is—

1. A fold-collar comprising a band and a folded-over top, said band having an upturned hook-end, the upper edge of which hook-end is convexly curved adjacent to the point of junction of said hook-end with the top, the other end of the collar having a corresponding interlocking part.

15 2. A fold-collar comprising a band and a folded-over top, said band having a hook-end and having its upper edge divergently convexly curved on opposite sides of and adjacent to the point of junction of said hook-end with the top, the other end of the

collar having a corresponding interlocking part.

3. A fold-collar comprising a band, and a folded-over top attached to the body-portion of the band, the upper edge of the attached portion of the band being convexly curved adjacent to the points of junction of the ends of the top with the band, said band having a hook-end the upper edge of which is convexly curved and intersects said convexly curved edge on the neighboring attached portion of the band substantially at the point of junction of the neighboring end of the top with the band.

In testimony whereof, I have hereunto set my hand this 23rd day of July, 1914.

HUBBARD F. HURD.
